(57) **CLAIM**

The ornamental design for an amusement game station, as shown and described.

DESCRIPTION

FIG. 1 is a top plan view of an amusement game station; FIG. 2 is a left side elevational view of the amusement game station;

FIG. 3 is a right side elevational view of the amusement game station;

FIG. 4 is a front elevational view of the amusement game station;

FIG. 5 is a rear elevational view of the amusement game station;

FIG. 6 is a top perspective view of the amusement game station shown in condition of use;

FIG. 7 is an enlarged view of the actuator portion of the amusement game station as designated in FIG. 6; and,

FIG. 8 is an enlarged view of the actuator portion of the amusement game station as designated in FIG. 3.

The broken lines showing the front edge of the amusement game station depict a portion that form no part of the claim. The broken lines around the magnified cuts, depict bounds of the enlarged portions and form no part of the claim.

1 Claim, 6 Drawing Sheets
